UNITED STATES PATENT OFFICE.

GEORGE A. HUMPHREY, OF NEW YORK, N. Y.

SELF-HEATING SAD-IRON.

1,086,453.

Specification of Letters Patent. Patented Feb. 10, 1914.

Application filed March 19, 1913. Serial No. 755,532.

To all whom it may concern:

Be it known that I, GEORGE A. HUMPHREY, a citizen of the United States, residing at the city of New York, N. Y., have invented certain new and useful Improvements in Self-Heating Sad-Irons, of which the following is a specification.

This invention relates to improvements in self-heating sad irons.

10 The main objects of this invention are: First, to provide an improved self-heating sad iron which is very efficient,—that is, one which may be quickly heated to any desired temperature and maintains a substantially even temperature, and one which is economical in fuel consumption. Second, to provide an improved self-heating sad iron in which the heat is effectively delivered to the bottom of the iron and the bottom of the iron is 15 evenly heated. Third, to provide an improved self-heating sad iron which may be very easily and conveniently manipulated.

Further objects, and objects relating to structural details, will definitely appear 20 from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

35 Figure I is a perspective view of a structure embodying the features of my invention. Fig. II is a vertical longitudinal section on a line corresponding to line 2—2 of Fig. III. Fig. III is a horizontal section 40 on a line corresponding to line 3—3 of Fig. II. Fig. IV is a detail transverse vertical section on a line corresponding to line 4—4 of Fig. III. Fig. V is an inverted perspective view of the burner body with the burner 45 thereon. Fig. VI is an enlarged detail view partially in section, on a line corresponding to the broken line 6—6 of Fig. II.

In the drawing, similar reference characters refer to similar parts throughout the 50 several views, and the sectional views are taken looking in the direction of the little arrows at the ends of the section lines.

Referring to the drawing, the body 1 of my improved sad-iron is a chambered cast- 55 ing. The inner side of the bottom is provided with an outer channel 2 adjacent the

walls and an inner longitudinal channel 3. Between the outer and inner channels is a series of pockets or recesses 4, 5, 6, 7 and 8. There is a single recess 4 arranged at the 60 front end of the iron, the recesses 5, 6, 7 and 8 being arranged in opposed pairs. See Fig. III.

The walls of the front recess 4 and of the front pair of recesses 5 are higher on their 65 inner sides,—that is, adjacent the inner channel 3, so that in effect, these recesses open into the outer channel 2. The outer walls of the recesses or pockets 6 are higher than the inner walls, so that these recesses in 70 effect open into the central or inner channel 3. The side walls of the recesses 7 and 8 are of substantially the same height so that these recesses open into both the inner and outer channels. The walls are provided 75 with air openings 11 which open into the outer channel, the lower edges of the openings being substantially flush with the bottom of the channel.

The top 12 is chambered to receive the 80 burner body 13. The upper edges of the walls of the body are notched at 14 to provide elongated air openings between the top and the body. The top is secured upon the body by means of the screws 15. The burner 85 body 13 is tubular and is secured in the top by the screw 16.

The tubular burners 17 are arranged on the body to project downwardly therefrom and are directed toward the pockets or recesses, their lower ends being quite close to the bottom so that the jets issuing therefrom 90 strike or impinge in the recesses.

The mixing tube 18 is arranged through the rear wall of the top to project into the 95 burner body, as clearly shown in Fig. II, and is adjustably retained by the set screw 19. The handle 20 is secured to the top by means of the screws 21, the screws being arranged through spacing members 22, the deflector plate 23 above the spacing members 90 and the spacing or insulating members 24 above the plate. This provides an effective heat insulating connection for the handle to the top.

The nozzle 25 is carried by the depending 100 bracket arm 26 secured to the rear end of the handle. The nozzle is provided with a regulating needle valve 27, and with a control valve 28 having a port 29 therethrough, 110 and an annular passage-like port 30 which registers at all times with the gas passage

31 of the hose nipple 32. The gas can be cut down to a minimum when the user desires to leave the iron temporarily. The valve is provided with a lever-like finger piece 33 having a laterally-turned end 34. The mixing tube 18 serves as a stop for this finger piece in one position, and the arm of the bracket for the other position. The nozzle is thus supported in operative relation to the 10 mixing tube, but being supported by the handle, which is effectively insulated, the heat is not transmitted to the nozzle and through it to the gas hose or tube.

It will be understood that these irons are 15 to be used with a flexible hose or conduit, and one serious objection has heretofore been that the heat transmitted to the hose would soon destroy the same or interfere with the effective delivery of the gas. By 20 arranging the parts in this manner, the gas is delivered to the mixing tube in a comparatively cool condition, and the delivery tube is protected from the heat so that it is not injured or destroyed thereby.

25 The arrangement of the burners is substantially that shown in my application for patent filed June 6, 1912, Ser. No. 701,741. My present structure, however, is an improvement upon the structure there illustrated, in certain particulars.

30 The heat is effectively delivered to the bottom of the iron, and further, all of the burners are supplied with the necessary air at the point of combustion so that perfect 35 combustion results, not only in utilizing all of the fuel delivered, but delivering the heat in a very effective manner.

Having thus described my invention, what 40 I claim as new and desire to secure by Letters Patent is:

1. In a self-heating sad iron, the combination of a chambered body having a bottom provided with an outer channel adjacent the walls and an inner longitudinal 45 channel and a plurality of recesses disposed between the inner and outer channels, there being a single recess at the front end, the other recesses being arranged in opposed pairs, the walls of the front and the first 50 pair of recesses being higher on the inner side, the walls of the central recesses being higher on the outer side, the side walls of the rear pairs of recesses being of substantially the same height, the walls of the iron 55 being provided with air openings opening into the outer channel; a top; and downwardly projecting burners arranged with their tips directed toward the recesses and adjacent to the bottom.

60 2. In a self-heating sad iron, the combination of a chambered body having a bottom provided with an outer channel adjacent to the walls and an inner longitudinal channel and a plurality of recesses disposed 65 between the central and outer channels, the

walls of a part of the recesses being higher on the inner side and those of another part being higher on their outer side, the side walls of the iron being provided with air openings opening into the outer channel; a 70 top; and downwardly projecting burners arranged with their tips directed toward the pockets and adjacent to the bottom.

3. In a self-heating sad iron, the combination of a chambered body having a bottom 75 provided with an outer channel adjacent the walls and an inner longitudinal channel, and a plurality of recesses disposed between the inner and outer channels, the walls being provided with air openings 80 opening into the outer channel; a top; and downwardly projecting burners arranged with their tips directed toward the recesses and adjacent to the bottom.

4. In a self-heating sad iron, the combination of a chambered body having a bottom provided with an outer channel adjacent to the walls, an inner longitudinal 90 channel and a plurality of recesses between the channels, the side walls being provided with air openings opening into the outer channel; a top; there being air openings 95 between the top and the body; a burner body arranged within the top; and tubular burners arranged on said burner body with their tips directed toward the recesses and adjacent to the bottom.

5. In a self-heating sad iron, the combination of a chambered body having a bottom provided with a channel adjacent to the 100 walls, and a plurality of recesses, the side walls being provided with air openings opening into the channel; a top; and downwardly-projecting burners arranged with their tips directed toward the recesses and adjacent to the bottom.

6. In a self-heating sad iron, the combination of a chambered body having a bottom provided with a channel adjacent to the walls, the walls being provided with air 110 openings opening into the channel, a top, and downwardly projecting burners arranged with their tips adjacent to the portion of the bottom within the said channel and disposed so that the flow of the jets is 115 outwardly toward the channel.

7. In a self-heating sad iron, the combination of a chambered body having a bottom provided with a channel adjacent to the walls, the walls being provided with air 120 openings opening into the channel, a top, and burners disposed above the portion of the bottom within the said channel to deliver downwardly so that the flow of the jets is outwardly and toward the channel.

8. In a self-heating sad iron, the combination with a chambered body provided with walls having air openings adjacent the bottom, and notch-like openings in their upper edges; a chambered top removably secured 130

- to said body; a burner body arranged within said top and carried thereby; a plurality of tubular burners arranged on said body to project downwardly therefrom with their tips adjacent the bottom; a handle mounted on said top, there being spacing members between the handle and the top to provide a heat insulating connection between the handle and top; a mixing tube arranged through the rear wall of the top to project into the burner body; a gas delivery nozzle; and a depending nozzle supporting bracket on said handle whereby said nozzle is supported in a spaced operative relation with said mixing tube, said bracket being provided with a conduit nipple and a nozzle regulating valve and a controlling valve.
9. In a self-heating sad iron, the combination with a chambered body, a top, there being air openings between the top and body, a burner, a mixing tube carried by and projecting from said top and communicating with said burner, said mixing tube being adjustably supported, a handle mounted on said top, there being spacing members to provide a heat insulating connection between the handle and top, a gas delivery nozzle, and a nozzle supporting bracket on said handle whereby the said nozzle is supported in a spaced operative relation to said mixing tube, said bracket being provided with a conduit nipple and a nozzle regulating valve and a controlling valve.
10. In a self-heating sad iron, the combination with a chambered body, a top, there being air openings between the top and body, a burner, a mixing tube carried by and projecting from said top and communicating with said burner, a handle mounted on said top, there being spacing members to provide a heat insulating connection between the handle and top, a gas delivery nozzle, and a nozzle supporting bracket on said handle whereby said nozzle is supported in operative relation to said mixing tube, but independently thereof, said bracket being provided with a conduit nipple and a nozzle regulating valve and a controlling valve.
11. In a self-heating sad iron, the combination with a chambered body, a top, there being air openings between the top and body, a burner, a mixing tube carried by
- 5 and projecting from said top and communicating with said burner, said mixing tube being adjustably supported, a handle mounted on said top, there being spacing members to provide a heat insulating connection between the handle and top, a gas delivery nozzle, and a nozzle supporting bracket on said handle whereby said nozzle is supported in a spaced operative relation to said mixing tube.
12. In a self-heating sad iron, the combination with a chambered body, a top, there being air openings between the top and body, a burner, a mixing tube carried by and projecting from said top and communicating with said burner, a handle mounted on said top, there being spacing members to provide a heat insulating connection between the handle and top, a gas delivery nozzle, and a nozzle supporting bracket on said handle whereby said nozzle is supported in operative relation to said mixing tube.
13. In a self-heating sad iron, the combination with a chambered body, a removable top, a burner carried by the top, a mixing tube carried by the top and communicating with said burner, a handle mounted on said top, a gas delivery nozzle, and a nozzle supporting bracket on said handle whereby said nozzle is supported in operative relation to said mixing tube, but independently thereof, said bracket being provided with a conduit nipple and a nozzle regulating valve and a controlling valve.
14. In a self-heating sad iron, the combination with a chambered body, a removable top, a burner carried by the top, a mixing tube carried by the top and communicating with said burner, a handle mounted on said top, a gas delivery nozzle, and a nozzle supporting bracket on said handle whereby said nozzle is supported in operative relation to said mixing tube, but independently thereof.
- In witness whereof, I have hereunto set my hand and seal in the presence of two witnesses.
